UNITED STATES PATENT OFFICE

GEORGE H. JUNG, JR., OF CINCINNATI, OHIO, ASSIGNOR TO THE JUNG ARCH BRACE COMPANY, OF CINCINNATI, OHIO, A CORPORATION OF OHIO

METHOD OF PREPARING ELASTIC WEBBING FOR CUTTING

Application filed May 30, 1930. Serial No. 457,593.

This invention relates to a method of treating elastic webbing to preclude recession of the elastics thereof into the fabric.

An object of the invention is to treat elastic webbing, comprising inelastic fibres and interwoven elastic elements, so that a given portion, severable from a larger unit of the elastic webbing and subjected to tension in a stretchable article, will not lose part of its elasticity due to recession of the elastic elements thereof into the webbing when in a stretched condition.

Another object is to provide a novel means of securely anchoring the elastic elements along a severed edge of elastic webbing.

Another object is to provide a flexible binding for an edge of elastic webbing.

These and other objects are attained by the means described herein and disclosed in the accompanying drawing, in which:

Fig. 1 is a top plan view of a strip of webbing having interwoven with the fabric thereof a series of longitudinal elastic elements.

Fig. 2 is a side elevational view showing the method of treating the strip.

Fig. 3 is a perspective view showing the effect upon the elastics produced by the treating of the strip of webbing.

Fig. 4 is a view similar to Fig. 2 showing how the treating operation may be performed while the elastic webbing is in stretched or partly stretched condition.

Fig. 5 is a plan view showing how elastic webbing, treated in accordance with the invention, may be joined to provide a serviceable, single thickness joint.

In the manufacture of elastic webbing which consists of interwoven fibres and elastic elements, usually of rubber, the elastic elements either are deliberately stretched during the weaving operation in order to insure a tight weave when stretched and elongated by reason of the lateral pressure exerted thereon by the weaving which envelopes them. In Fig. 1 is disclosed a strip of elastic webbing comprising the interwoven fabric body 6 and the longitudinal spaced parallel elastic elements 7. When such a strip of elastic webbing is cut from a continuous reel or roll

and subsequently used in a stretchable article, the elastic elements invariably recede into the webbing unless they are firmly anchored at the severed ends. The use of stitching and adhesive tape for anchoring said ends has not proven entirely satisfactory because of the damaging effect of the sewing needle on the elastics, and the liability of the stitching and tape to loosen.

The foregoing disadvantages are obviated by applying to the webbing 6, transversely thereof, a narrow coating 9 of fluid cement, such as rubber cement, and then placing thereon a strip 10 of uncured rubber, the strip and webbing being then placed between the heated elements 11 and 12 of a vulcanizing device which vulcanizes the uncured rubber to each of the elastic elements, through the fabric. The elastic elements are thereby joined, as indicated diagrammatically in Fig. 3. With the elastic elements thus joined, and secured also to the fabric of the webbing, a cut may be made centrally of the vulcanized portion 13, as indicated by broken line 14, unattended by recession of the elastic elements into the fabric with the undesirable results above mentioned. Even though the vulcanizable substance may not under some conditions securely attach itself to the elastic elements, the resultant binding or setting of the fabric of the webbing serves to securely hold the elastic elements.

The vulcanizer heating and pressing members may be electrically or otherwise heated, the characters 15, 16 and 17 indicating the usual resistances, sources of electricity, and switches, respectively. While vulcanization by heat is considered a preferable expedient for securing uncured rubber to other rubber articles, it is to be understood that the present invention is not to be limited to the use of uncured rubber for securing the elastic elements, nor to the use of heat for effecting union of the elastic elements, with one another and with the fabric. It is anticipated that a suitable binder substance not requiring the application of heat may be procured which will join the elastic elements as effectively as will vulcanization.

As indicated in Fig. 4, the elastic webbing

may be stretched during the application of the cement and uncured rubber strip, and held so during the vulcanizing operation by any suitable means such as clamps 18. This facilitates entry of the cement and rubber between the fibres of the webbing during the treatment. As indicated at 8, (Fig. 1) the vulcanizing process may be applied to the edge of the webbing subsequent to the cutting operation if desired.

In Fig. 5 is illustrated the simple and servicable connection that may be made, using the improved webbing, without overlapping the webbing or applying one or more thicknesses of adhesive tape thereto. The treated edge 20, from which the elastics cannot recede, is placed in abutment with an edge 21 of webbing or other material 22, whereupon the simple cross-stitching 23 may be applied for holding the edges in abutting relationship. This construction provides a single thickness connection which would cause no discomfort to a wearer when applied to bandages, supports or wearing apparel. Developments in the art of scientifically designed elastic bandages, arch braces and the like demand that the elasticity of the webbing be preserved so that each elastic element may share in scientifically supporting affected parts of the injured or affected portion of the human body. When such bandages and supports are stitched or sewed to retain the elastic elements in position, one or more of the elastic elements invariably are broken, weakened, or lost in the sewing operation. The present invention provides a means whereby the elastic elements are kept under control for perfectly supporting the affected parts.

What is claimed is:

- 40 1. The method of cutting to preclude recession of the elastic elements in elastic webbing comprising applying to the elastic webbing along the line of cutting a fluid cement adapted to penetrate the fibres of the webbing and to contact the elastic elements, applying to the cement a strip of uncured rubber, vulcanizing the cement and uncured rubber to each of the elastic elements, then cutting the elastic webbing centrally of the vulcanized portion thereof.
- 45 2. The method of cutting to preclude recession of the elastic elements in elastic webbing comprising stretching the elastic webbing, applying to the elastic webbing along the line of cutting a fluid cement adapted to penetrate the fibres of the webbing and to contact the elastic elements, applying to the cement a strip of uncured rubber, vulcanizing the cement and uncured rubber to each of the elastic elements while the elastic webbing is stretched, then cutting the elastic webbing centrally of the vulcanized portion thereof.
- 50 3. The method of cutting to preclude recession of the elastic elements in elastic web-

bing comprising stretching the elastic webbing, applying to the elastic webbing along the line of cutting a substance for binding the elastic elements to one another while the elastic webbing is stretched, then cutting through the substance along the line of cutting.

4. The method of anchoring the elastic elements of elastic webbing, comprising applying a vulcanizable substance to the surface of the webbing while stretched and then vulcanizing said substance to the elastic elements through the webbing.

5. The method of anchoring in a predetermined area the elastic elements of elastic webbing, comprising applying a binding substance to the surface of the webbing in said area while the webbing is in a stretched condition.

In testimony whereof I have hereunto subscribed my name this 27th day of May, 1930.

GEORGE H. JUNG, JR.
